CLAIM

The ornamental design for a handheld shock wave device, as shown and described.

DESCRIPTION

FIG. 1 is a perspective view of a handheld shock wave device showing our new design;

FIG. 2 is a top plan view of the handheld shock wave device of FIG. 1;

FIG. 3 is a bottom plan view of the handheld shock wave device of FIG. 1;

FIG. 4 is a left side elevational view of the handheld shock wave device of FIG. 1;

FIG. 5 is a right side elevational view the handheld shock wave device of FIG. 1;

FIG. 6 is a front side elevational view of the handheld shock wave device of FIG. 1; and,

FIG. 7 is a rear side elevational view of the handheld shock wave device of FIG. 1.

The broken lines shown in the drawings illustrate portions of the handheld shock wave device that form no part of the claimed design.
